(30) **Foreign Application Priority Data**(57) **CLAIM**

Oct. 28, 2009 (EM) DM/072 615

I claim the ornamental design for a portion of a side and quarter of a footwear article, as shown and described.

(51) **LOC (9) Cl.** ..... **02-99****DESCRIPTION**(52) **U.S. Cl.** **D2/972**

FIG. 1 is a side, rear perspective view of a portion of a side and quarter of a footwear article; and,

(58) **Field of Classification Search** D2/896,

FIG. 2 is a side elevation view of the side and quarter of the footwear article of FIG. 1.

D2/902, 906-908, 943, 944, 969, 972-974;

The ornamental design that is claimed is shown in solid lines in the drawings. The broken (dashed) lines shown in FIGS. 1 through 2 are included for the purpose of illustrating environmental elements only and form no part of the claimed design.

36/45-49, 50.1, 77 M, 77 R, 83, 88, 113,

36/114, 126-131

See application file for complete search history.
